VOTING MACHINE

Alvin N. Gustavson, Jamestown, N. Y., assignor
to Automatic Voting Machine Corporation, a
corporation of Delaware

Application August 22, 1939, Serial No. 291,375

2 Claims. (Cl. 235—54)

This invention relates to an improvement in voting machines and more particularly to a device adapted to register the number of voters casting ballots on certain issues or for one or more candidates to certain offices.

In certain localities there are election laws concerning the nomination or election of candidates to local offices. These laws have application to the nomination of candidates to participate in political party conventions, election of members to boards of education, supervisors, etc. In substance, these laws require that a specified majority of voters must have balloted for one or more candidates for a given office before the candidates having the greatest number of votes can be declared elected. It is the purpose of these laws to determine the will of the majority of voters and, therefore, the majority is based not on the total number of votes received by one or all candidates, but rather on the total number of voters who have balloted for one or more of the candidates for a given office. The actual majority percentage may vary in different communities or in the nomination or election of candidates to different offices.

The present invention contemplates provision of a device applicable to a voting machine for the purpose of separately registering the number of voters who have cast a ballot for any candidate for a given office when there is more than one candidate seeking election to said office. The device includes a counter mechanism separate from the mechanisms that register ballots for candidates to various offices. The device is so arranged and constituted that should a voter move one of the indicators into voting position and, before completing his ballot concerning other issues and candidates to other offices, return said indicator to non-voting position, no registration would have been made. However, if the indicator remains in voted position, the counter mechanism of the device will be advanced once simultaneously with the registration of the voter's other choices.

Through use of the present invention, it is possible, following an election, to determine how many voters of those who balloted cast a ballot for one or more of the candidates to a given office. This may be illustrated by the assumption that the election laws require a sixty percent majority of the voters who balloted to have indicated a preference for one or more of the candidates for a given office. For example, fifteen candidates are seeking election to a board of supervisors in which there is only five vacancies, and

one thousand voters have indicated their choice of candidates for numerous other offices. Of the thousand voters, seven hundred cast ballots for from one to five of the fifteen candidates seeking election to the board of supervisors. At the completion of the election, the counter mechanism of the present invention will disclose that seven hundred voters had balloted, thus satisfying the election requirement of a sixty percent majority. The five candidates receiving the greatest number of votes would, therefore, be elected to the board of supervisors. On the other hand, if at the close of the election, the counter mechanism indicated that only five hundred of the thousand voters had shown sufficient interest in the candidates for supervisors to vote for one or more, the election laws would not be satisfied and the vacancies on the board of supervisors could not be filled since the result was not representative of the preference of a sixty percent majority of actual voters.

The principal advantages and objects of the invention lie in the provision of a device that serves to eliminate the need of special elections by making possible the use of a voting machine at a general or primary election for special purposes. The invention also adapts a voting machine to meet the requirements of certain municipal election laws and its convenience of installation, adaptability for use in voting machines of different sizes, accuracy of operation and simplicity of construction constitute further advantages.

Other objects and advantages will be more fully understood from a consideration of the following specification taken in conjunction with the accompanying drawing, and in which

Fig. 1 is a fragmentary front elevational view of a portion of the keyboard of a voting machine, parts thereof being broken away to illustrate the arrangement and position of one form of the invention;

Fig. 2 is a horizontal sectional view taken substantially on the line 2—2 of Figure 3;

Fig. 3 is a vertical sectional view on a somewhat smaller scale, being taken substantially on the line 3—3 of Figure 1;

Fig. 4 is a fragmentary vertical sectional view, being taken substantially on the line 4—4 of Figure 2;

Fig. 5 is a side elevational view of the counter mechanism of the device, parts being broken away to disclose certain structural details;

Fig. 6 is a fragmentary front elevational view

of the counter mechanism prior to being set for registering; and

Fig. 7 indicates the same mechanism in position for registering.

Reference is now had to the drawing wherein the numeral 10 is employed to generally designate a portion of a voting machine. Conventional voting machines are provided with candidate indicators 11 that are arranged in vertical and horizontal rows. The rows of one direction are generally referred to as party rows and those in the other direction as office rows. In the present illustration it is assumed the vertical rows designate the office and the horizontal rows the party, although this is frequently reversed to meet the election laws of certain communities. The indicators 11 are mounted in the front wall 12 of the voting machine and each includes a shaft 13 that, to the rear of the wall 12, supports a key 14. The key is U-shaped having arms 15 and 17. Arm 15 is secured to the shaft 13. Arm 16 mounts a pin 18 that is engageable with a counter mechanism. The portion 19 that connects arms 15 and 17 is slotted to receive one end of a main interlocking strap 21. This strap terminates at its lower end in an enlarged portion 22 that projects into a main grouping channel 23. This channel includes rollers 24, between each pair of which is located the neck-like portion 25 of two adjacent straps 21. Enlarged portions 22 are located within the channel and beneath the rollers 24. When one of the indicators 11 is manipulated, the interlocking strap 21 is raised causing the enlarged portion 22 to move upwardly between a pair of rollers, moving said rollers laterally apart and limiting, to a predetermined degree, further lateral displacement of the rollers upon the subsequent raising of other of said interlocking straps. Each interlocking strap 21, at a predetermined place between its ends, is formed with a ledge or shoulder 26. It will be understood that the rollers and main grouping channel are conventional structure and form no part of the present invention.

Mounted adjacent the side walls of the voting machine are frame members 27. These members are provided with angle brackets 28 that are suitably connected with the rear face of the wall 12. Suitable bearing means is provided in the members 27 to support the ends of a shaft 29. The shaft is rotatable and, in the present disclosure, is square in cross section intermediate its ends. As may be understood from the drawing, the shaft 29 is located to the rear of the interlocking straps 21 and adjacent the main grouping channel 23. A grouping member 30 is provided for the interlocking straps 21 and takes the form of a plate that at one end is suitably engaged with the shaft 29, being secured thereto in any manner as by a pin 31. The other end of the member 30 is formed with a downwardly extending flange 32 from the ends of which tabs 33 extend. The member 30 is of sufficient length to extend from the rod 29 into immediate proximity with the interlocking straps 21 and is adapted to enclose all of the straps 21 that relate to the indicators of one vertical row or office group. The flange 32 is adapted to rest on the ledges 26 of straps 21, the tabs 33 assuming a position substantially as indicated in the drawing.

Adjacent one of the frame members 27, one end of an arm 34 is fixed to the shaft 29. The other end of this arm is fitted with a pin 36 that pivotally mounts the upper end of a strap 37 and the lower end of a strap 38. Strap 37 is formed

with an offset portion 39 that brings it into alignment with the interlocking straps 21. The lower end of this strap terminates in a hook portion 41, indicated in dotted line in Figure 3. The hook portion is engageable with the lower edge of a reset bar 42 that, as may be seen in the drawing, projects through suitable slots in all of the interlocking straps. The reset bar is standard to voting machines of the type to which the present invention is applicable.

The strap 38, adjacent its connection with arm 34, is formed with a curved portion to bring it into alignment with the row of interlocking straps 21. The upper end of this strap is pivotally joined to the central portion of a key 43. This key, for convenience in construction, is identical with key 14. Key 43 is conveniently mounted on a shaft 44 and includes an arm 46 that is provided with a laterally directed pin 47.

The pin 47 projects into the open side of a vertically positioned channel shaped casing 48 that substantially encloses and mounts one or more counter mechanisms. As may be seen in the drawing, the end of the pin lies between a pair of connected disks 49 that are slidably carried on a shaft 51. Shaft 51 is supported by the side walls of the casing 48. One of the disks 49 carries a gear segment 52 that, when the disks are moved laterally of the casing 48 along shaft 51, is engageable with one of the gears of a counter 53. Rotation of the disks 49 is had by means of a yoke 54. This yoke includes side members 56, the upper ends of which are suitably connected. The side members are centrally pivoted on the shaft 51. Disks 49 are slotted and receive the portion that connects the side members 56. The free ends of the members 56 are pivotally joined to parallel bars 57. The upper ends of these bars are connected by a pin 58, that is, joined to one end of a strap 59. The other end of strap 59 is secured to or may be made integral with a rod 61. The rod 61 is joined to a conventional curtain release mechanism of the voting machine.

Inasmuch as the shaft 29 extends substantially the full width of the voting machine, as many grouping members 30 as required may be mounted thereon. Each grouping member is engaged with the interlocking straps 21 that are in turn connected with the indicators of one vertical row or office group.

Operation of the structure is as follows: It is assumed that the voting machine to which the invention is applied is in use at a general election and in addition the voters are to indicate their preference for a candidate to fill a vacancy in an office that comes within the special requirement hereinbefore mentioned. The voter having cast his ballot for the various candidates may cast a ballot for one of the candidates in the vertical row or office group indicated at A in Figure 1. This office group of indicators is connected by straps 21 with the grouping member 30 as already described. If any one of the indicators 11 in the office group A is moved to voted position such movement raises the connected interlocking strap 21, causing the ledge 26 thereof to elevate the end of the grouping member 30 and rotate shaft 29 in a clockwise direction as viewed in Figure 3. This movement of the shaft 29 rotates arm 34 causing straps 37 and 38 to move upwardly. The upper end of strap 38, being connected with the key 43 rotates this key about its shaft 44, thus causing pin 47 to move latterly within the counter cas-

ing 48. The disks 49 are thus latterly adjusted so that the gear segment 52 will be engageable with one of the gears of the counter 53. At this point it is brought out that the counter 48 has been set or conditioned for subsequent registering, but that should the voter wish to revoke his ballot and vote for another candidate, he may do so and the mechanism will unset or disable the counter. It is contemplated that on the return of a candidate indicator and attached strap to inoperative position, the parts connecting such strap with the counter will return by gravity or through the use of a conventional spring (not shown) to inoperative position. At such time as the voter has completed his ballot and operates a curtain release lever, the rod 61 is raised causing strap 59 to rotate yoke 54. Inasmuch as gear segment 52 is connected through disks 49 with the yoke, said segment will engage one of the gears of the counter causing the total on the counter to be increased by one. It is to be noted that simultaneously with the movement of the strap 38, strap 37 moves upwardly so that the hook portion 41 is fully engaged with the lower edge of the reset bar 42. Completing operation of opening the curtains lowers the reset bar 42 and causes arm 37 to move downwardly to the position in Figure 3, simultaneously with resetting the interlocking straps 21. This downwardly movement of the strap 37 moves arm 34 and causes shaft 29 to rotate in a counterclockwise direction. Thus the grouping member 30 is returned to original position with the flange 32 thereof resting on all of the ledges 26 of the straps 21 grouped by said member.

If the voter has not balloted for one of the candidates in office group A, the mechanism that serves to operate the counter 53 will not function. It is evident that the present invention is not necessary when there is only one candidate in the special office row A since the counter for the single candidate would signify the number of voters casting a ballot for him. The device is intended for use when there are more candidates than there are vacancies or offices to be filled and, through its use, it is possible to determine what percentage of the voters at a general election have indicated a preference for one or more of the candidates in the special office row A.

Although applicant has shown and described

only one modification of the invention applicable to one type of voting machine, it will be apparent to those skilled in the art that the device may be modified insofar as such modifications are within the spirit and scope of the invention as defined in the hereunto annexed claims.

Having thus set forth my invention what I claim as new and for which I desire protection by Letters Patent is:

- 10 1. In a voting machine having indicator actuatable straps provided with ledges that are disposed in the same horizontal plane when said straps are in an unoperated position, a counter, counter setting mechanism, an operative member connected with and adapted to move said counter setting mechanism into and out of counter setting position, said counter setting mechanism normally rendering said counter inoperative, arms on said member embracing and segregating a plurality of said straps, a flange on said member engaged with the ledges of all of the segregated straps, any one of said segregated straps being operable to move said member and said counter mechanism into operative position, and means for operating said counter when rendered operative by said setting mechanism.
- 15 2. In a voting machine having indicator actuatable straps provided with ledges disposed in the same horizontal plane when said straps are in an unoperated position, a reset bar associated with and operable to move all of said straps into an unoperated position, a counter, a counter setting mechanism, an operative member connected with and adapted to move said setting mechanism into and out of counter setting position, said setting mechanism normally rendering said counter inoperative, arms on said member so spaced as to embrace and segregate a predetermined number of said straps, said member intermediate said arms being engaged with the ledges of the segregated straps, any one of said straps being operable to move said member and said mechanism into operative position, means connecting said member with said reset bar and operable by said reset bar to return said member and said mechanism to inoperative and non-setting position, and means for operating said counter when rendered operative by said setting mechanism.
- 20 30 35 40 45 50

ALVIN N. GUSTAVSON.
